Primary Examiner — Rebekah A Caruso(74) *Attorney, Agent, or Firm* — Perry + Currier Inc.(57) **CLAIM**

The ornamental design for a smartwatch, as shown and described.

DESCRIPTION

FIG. 1 is a front and right side perspective view of a smartwatch showing our new design;

FIG. 2 is a rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a partial enlarged view of FIG. 1.

The broken lines showing various regions of the smartwatch represent subject matter which forms no part of the claimed design.

1 Claim, 9 Drawing Sheets(56)
